UNITED STATES PATENT OFFICE.

ERASTUS S. BENNETT, OF NEW YORK, N. Y.

BEARING FOR TURN-TABLES OR THE LIKE.

SPECIFICATION forming part of Letters Patent No. 769,460, dated September 6, 1904.

Application filed October 19, 1903. Serial No. 177,589. (No model.)

To all whom it may concern:

Be it known that I, ERASTUS S. BENNETT, a citizen of the United States, residing at New York city, New York, have invented certain 5 new and useful Improvements in Bearings for Turn-Tables or the Like, of which the following is a specification.

My invention has been devised for use in connection with mining machinery intended 10 more particularly for handling placer material, such machines comprising a scoop or dipper supported by a boom, which in turn is carried by a rotary table or platform. My invention, however, is not limited in its application to mining machinery, but may be employed in dredging or excavating machinery or in any apparatus wherein a boom or other part is supported and carried by a turn-table. It has been found from experience in machinery of this class that the weight of the parts is so great that ordinary bearings will 15 not stand the wear, and it is impossible to employ a bearing requiring lubrication, particularly at the points adjacent the connection between the boom and the turn-table, at which points the supporting strain of the boom is located.

By my invention I aim to provide an anti-friction roller-bearing between the turn-table 20 and the frame, said roller bearing or bearings being located adjacent the lower end of the boom where it connects with the turn-table.

The invention consists in the features, combination, and arrangement of parts, as will be 25 hereinafter described, and particularly pointed out in the claims.

In the accompanying drawings, Figure 1 is a plan view of a turn-table which is representative of such table as used on a mining, 30 excavating, dredging, or any other machine of this class. Fig. 2 is a side view of Fig. 1. Figs. 3 and 4 are respectively side and plan views of the ordinary form of roller-bearing arranged between the turn-table and the main 35 frame or platform of the machine. Fig. 5 is a vertical sectional view across one of the I-beams to which the boom is pivoted, showing also a part of the platform in section and my improved form of bearing in connection therewith. Fig. 6 is a sectional view through the

bearing, taken at right angles to the view shown in Fig. 5; and Fig. 7 is a plan view of the bearing.

In the drawings, 1 represents a turn-table of any suitable form, 2 the mast, and 3 3 the I-beams, supported on the turn-table on each side of the mast, arranged parallel with each other, and having at one end bearings 4 in which a cross shaft or rod 5 is supported, which forms the pivoted bearing of a boom 6. 60 This boom carries the dipper or scoop intended to take up the placer material or to do the excavating, and it, together with the boom and the operating connections associated with the dipper, are of great weight, and by my invention I sustain the weight of these parts in a special manner, as will be now described.

The improved bearings constituting my invention are located at the points 6^x, as shown in Figs. 1 and 2, adjacent the lower end of the boom and preferably between the angle-iron or I beams 3 and the main deck or platform 7. For this purpose the angle-iron or I beams have their vertical webs 8 provided with openings 9, and extending through these openings in the I-beams are track-sections 10, there being one track-section for each of the bearings. This track-section 10 is secured by bolts 11 to the upper side of the turn-table, and the said bolts 11 also hold in place a lower track-section 12 for each bearing, said lower track being held up against the lower face of the turn-table. The track-sections 10 and 12 of each bearing have horizontal faces or ways 13 and curved end portions 14, which when 85 the two track-sections are in place form, as shown in Fig. 5, semicircular end portions to the tracks. These track-sections are each provided with ribs 15 along their margins, and the surface 16 between these ribs forms the 90 bearing-surface for a series of rollers 17, connected together by links 18 into an endless chain, as shown in Fig. 5. The endless chain passes through openings 19 in the turn-table and encircles the tracks, as clearly shown in 95 said figure.

In order to protect the bearing from dust and dirt, a shield 20 is provided, extending from the turn-table 1 to the sides of the vertical web of the I-beam. The endless chain 100

of rollers bear upon a track 21, secured to the main deck or platform, and they sustain the weight of the platform and boom by affording antifriction support for the track 12 5 and the turn-table, to which said track is secured. As shown in Fig. 1, the antifriction-bearing extends concentric to the axis or mast of the turn-table, and this is illustrated also in Fig. 7. By reason of the concentric relation of the endless chain to the turn-table I 10 arrange the tracks 10 and 12 at a slight inclination, as shown at Fig. 6, and the rollers are slightly conical.

From the above it will be seen that I provide an antifriction-bearing needing no lubrication and located adjacent the point of connection between the boom and the turn-table, so as to sustain the weight of the boom and the parts carried thereby on the main deck 20 or platform.

I claim as my invention—

1. In combination with a boom of a shovel or dredge, a roller-bearing for sustaining the lower end of the said boom.
2. In combination with a turn-table, an antifriction-bearing comprising an endless chain of rollers passing above and below the said turn-table and arranged to bear on the main deck, substantially as described.
3. In combination with a turn-table, track-sections on the upper and lower faces of the same and an endless chain of rollers passing through openings in the turn-table and along the track-sections, said rollers bearing upon

the main deck or platform, substantially as 35 described.

4. In combination with a turn-table, an angle-iron or I beam supported thereon and having an opening therethrough and an antifriction-bearing consisting of an endless chain of 40 rollers extending to points on opposite sides of the angle-iron or I beam and between the turn-table and main deck, substantially as described.

5. In combination with a turn-table an angle-iron or I beam supported thereon, a boom pivoted to the angle-iron, said angle-iron having an opening therethrough, an antifriction-bearing comprising track means on the upper and lower faces of the turn-table and an endless chain of rollers passing around the said track through openings in the turn-table and through the openings in the angle-iron, substantially as described.

6. In combination with a turn-table, a pair 55 of angle-iron beams supported thereon parallel with each other, a boom pivoted between the said angle-irons and an antifriction-bearing at each of the angle-irons consisting of an endless chain of rollers operating between the turn-table and the main deck and below the angle-iron, substantially as described.

In testimony whereof I affix my signature in presence of two witnesses.

ERASTUS S. BENNETT.
